UNITED STATES PATENT OFFICE.

WILLIAM P. QUENTELL, OF NEW YORK, N. Y., ASSIGNOR TO QUENTELL CORPORATION, OF NEW YORK, N. Y., A CORPORATION OF NEW YORK.

TRANSFER MECHANISM FOR REGISTERS.

Application filed May 21, 1923. Serial No. 640,432.

To all whom it may concern:

Be it known that I, WILLIAM P. QUENTELL, a citizen of the United States, residing at New York, county of New York, State of New York, have invented a certain new and useful Improvement in Transfer Mechanism for Registers, of which the following is a specification, reference being had therein to the accompanying drawings.

10 This invention relates to transfer or tens carrying mechanism for registers, and especially, although not exclusively, to carrying mechanism for key set, lever or power operated adding machines, that is to say, 15 adding machines of the type in which the register is operated to effect the adding, not directly by actuation of the keys, but by independent operating mechanism which moves the register in a manner and to an 20 extent determined by a previous setting of the keys.

In machines of this type, the carrying of the tens from an adding or registering wheel or element of a lower order to one of the next higher order is usually effected through a cam or equivalent device on or 25 operated by the element of the lower order when it passes through its "zero" position, which cam or the like operates a member 30 which releases the mechanism for moving the element of the higher order one space in order to register the decimal or tens carry-over. Mechanism of this character operates quite satisfactorily when the machine is operated slowly, or when the adding wheel of 35 the lower order is moved through a small distance only, as from the "nine" position to the "zero" position, but when the machine is operated at a high speed and the 40 adding wheel of the lower order is rotated rapidly for a considerable distance (as for example from the "zero" position) into its "nine" position, the cam carried thereby strikes a sharp blow upon its cooperating 45 member, tending to throw the same beyond the cam and releases the carrying mechanism, so that, unless the parts are very accurately made and adjusted, or the speed regulated, carrying will improperly take 50 place when the wheel of the lower order is brought to the "nine" position instead of when it is brought to or through the "zero" position.

The present invention has for its object 55 to provide a carry control mechanism not

requiring great accuracy in its adjustment, or dependent upon speed regulation, but in which danger of improper carrying, as above described, is eliminated, and to this end said mechanism comprises a carry control member for each registering element which is not directly operated by the cam to release the carrying mechanism, but which is so arranged as to release the carrying mechanism when it is itself released by the cam, after having first been engaged and moved thereby. This operation can occur at any point between the "nine" and the "zero" position of the corresponding adding wheel or equivalent registering element, 70 so that the parts can be set with much less precision than that required in the setting of mechanism of the type usually employed, but will nevertheless act with absolute accuracy.

The foregoing and other objects of the invention, together with means whereby the same may be carried into effect, will best be understood from the following description of one form or embodiment thereof illustrated in the accompanying drawings. It will be understood, however, that the particular construction and application of the invention described and shown has been chosen for illustrative purposes merely, and that said invention, as defined by the claims hereunto appended, may be otherwise practiced without departure from its spirit and scope.

In said drawings:

Fig. 1 is a front elevation, partly broken away, of a portion of an adding machine embodying the invention.

Fig. 2 is a section taken substantially on the line 2-2 of Fig. 1.

Figs. 3, 4 and 5 are sections taken substantially on the lines 3-3 of Fig. 1, showing the parts in different positions assumed thereby during the cycle of operations of the mechanism, the position of the rack for operating the adding wheel of the order next lower than that of the number wheel shown being indicated in each figure in broken lines.

For convenience, the terms "zero position", "one position", "eight position", "nine position", etc. are employed with reference to the adding wheels to denote the angular positions of said wheels, in accordance with the arrangement of the machine, in which

the numerals, "0", "1", "8", "9", etc. are registered thereby.

The mechanism embodying the invention is herein shown as forming a portion of an adding machine of well-known type, the details of which are not shown in full as such parts as are hereinafter referred to but not shown may be of any character or type well known in the art.

- 10 The frame of said machine comprises side plates 15 connected and spaced by suitable rods, one of which is indicated at 16. Journalled in the side plates 15 is a main operating shaft 17 which is oscillated by a crank 5 or other well-known mechanism at each adding operation and by means of which the various instrumentalities of the machine are operated. As herein shown, said shaft 17 carries adjacent its opposite ends respectively a pair of cams 18 for operating and controlling the carrying mechanism herein-after described. Each of said cams is formed with relatively low and high concentric portions 181 and 182 separated by a projection 180. Mounted to rock upon the rod 16 is an adding wheel frame 19 carrying a longitudinal rod 20 upon which are loosely or rotatably mounted the adding wheels 21. Said adding wheels may be of any desired 15 number, and as herein shown comprise cup-like members or drums bearing upon their peripheries the several digits from "0" to "9" in series, each of said wheels being, in the construction shown, provided with two 20 complete series of digits. Secured to each adding wheel 21 is a gear 22 adapted to be engaged and operated by a vertically movable rack 24. The adding wheel frame 19 normally occupies a position in which the 25 gears 22 are held out of mesh with their respective racks 24. Operation of the keys (not shown) of the machine permits the racks 24 to be raised to a greater or less extent, depending upon the particular key or 30 keys depressed. At the end of the forward stroke of the operating mechanism (in the present instance a counter-clockwise movement of the shaft 17 and parts carried thereby) the adding wheel frame 19 is rocked 35 upon the rod 16 to move the gears 22 into mesh with their respective racks 24. At the beginning of the return stroke of the operating mechanism, the racks 24 are returned to their normal position, thereby turning the 40 gears 22 and number wheels 21 an amount depending upon the previous setting of said racks, as shown in Figure 3. The mechanism thus far referred to is well known in the art and will be understood without further description.
- Secured to each of the adding wheels 21 at the side thereof adjacent the wheel of next higher order, is an arm 25 having at its end a cam 26 coaxial with said wheel and 45 also rotatably mounted on the rod 20. Each of said cams is formed with two raised portions 260 (corresponding in number to the two series of digits of each number wheel), each of said raised portions being of an angular length corresponding approximately 50 to three digit spaces of the number wheel, and each terminating in an abrupt shoulder.
- Each of the adding wheels 21 is normally locked against accidental rotation by engagement of its gear 22 by a tooth 280 on a carrying member 28, there being a carrying member for each wheel and gear. The carrying members 28 are mounted in a frame 29 having end flanges 290 which are secured to the side plates 15 of the machine's frame, 55 said frame 29 having also top and bottom flanges 291 and 292 formed with slots in which all of said carrying members, with the exception of that corresponding to the adding wheel of lowest order, are guided for 60 vertical sliding movement. Rods 30 and 31 carried by the frame 29 extend through all of the carrying members 28. The carrying member 28^a corresponding to the adding wheel of lowest order is held in fixed position by said rods, while the remaining carrying members 28 are formed with slots 32 to receive said rods, thereby permitting said members a limited vertical movement. Each 65 of said members 28 (with the exception of the member 28^a) is formed on one side with a lug 33 connected by a spring 34 with the upper rod 30, said springs tending normally to move said members upwardly. Said members 28 are normally locked against 70 movement by the springs 34 by means of latches 35 pivoted upon the rod 31 and engaging lugs 36 projecting from said members at the side opposite the lugs 33. The latches 35 are formed with ears 37 which extend through slots in the frame 29 so as to 75 position said latches laterally on the rod 31 and are connected by springs 38 with said frame, said springs tending normally to force said latches into engagement with the lugs 36, thereby normally locking the carrying members 28 against upward movement under the influence of their springs 34, as 80 shown in Figures 1 and 2.
- Mounted on a rod 40 in the adding wheel frame 19 is a series of carry control members in the form of yokes 41 corresponding in number and arrangement to the number wheels and connected with the adding wheel frame 19 by springs 61. Each of said carry control members comprises an arm 410 having an angular end 411 co-operating with the cam 26 of the corresponding number wheel. Each of said carry control members also comprises a finger 412 which extends 85 through a slot 195 in the adding wheel frame and which is adapted, when the end 411 of the arm 410 passes into engagement with a low portion of the cam 26, to strike the angularly turned end 42 of an arm 43 on 90

the corresponding latch 35 and thereby release said latch from the lug 36 of the corresponding carrying member 28.

- Co-operating with the several yokes 41 are 5 latches 44 in the form of yokes mounted on the shaft 16. Each of said latches 44 is formed with a cam portion 440 terminating in a tooth 441, which parts engage the cross or intermediate portions of the yokes 41. 10 The latches 44 are guided in slots in a bail 45 having side portions 450 pivoted to the rod 16 and formed with extensions 50 for a purpose hereinafter described. The bail 45 is connected with the several latches 44 by 15 means of springs 46.

Pivoted at 47 to the outside faces of the side plates 15 are rockers 48 provided with anti-friction rollers 49 which co-operate with the cams 18. Pivoted at 51 to the inside faces of the plates 15 are latches 52 having springs 53 tending normally to move the same in a clockwise direction from the position shown in Figure 2, said latches having also laterally turned lips 54 which co-operate with pins 55 on the cams 18. A bail 56 is mounted on the rod 16 and extends over forwardly projecting horns 281 formed on the lower ends of the carrying members 28, the forwardly extending sides 25 of said bail being engaged by inwardly turned lips 60 on the rockers 48 and terminating in hook-shaped ends 560 which co-operate with laterally offset portions of the latches 52.

35 In Figure 2, the cam 26 is shown in the position occupied thereby when the adding wheel to which it is attached is in the "one" position; in Figure 3, when its wheel is in the "nine" position; and in Figures 4 and 40 5, when said wheel is in the "zero" position.

As shown in Figure 2, each carry control member 41 is held by its latch 44 in a position intermediate its limits of oscillation with the end 411 of its arm 410 in the 45 position it would occupy were it resting upon one of the cam projections 260 with the corresponding adding wheel 21 in approximately the "eight" position. When so held, the arm 412 permits the corresponding 50 latch 35 to occupy its operative position in engagement with the lug 36 of its carrying member 28. When the adding wheel 21 is rotated forwardly (that is, in a counter-clockwise direction as shown in the drawings) into the "nine" position, as shown in 55 Figure 3, one of the cam projections 260 will move or raise the arm 410 beyond the point where it is held by the latch 44, thereby lifting the yoke 41 out of engagement with said latch. When this occurs, said latch is drawn away from said yoke by the 60 spring 46. Thereafter, should the cam 26 be further turned into a position corresponding to the "zero" position of its adding wheel, as shown in Fig. 4, the end 411

of the arm 410 will drop from the abrupt shoulder of the cam projection 260, causing the spring 61 to lift the finger 412 which, by striking the end 42 of the projection 43, disengages the latch 35 from the lug 36 and releases the corresponding carrying member 28. The shape of each finger 412 is such that, when its yoke 41 occupies its normal position as shown in Fig. 2, the operative end of said finger follows substantially the 70 arc of a curve concentric with the shaft 16, thereby avoiding improper operation of the carrying member latches when the adding wheel frame is rocked. 75

The complete operation is as follows: 80

In Figure 2 the parts are shown in the positions occupied thereby after a blank stroke of the machine. Let it be assumed that the proper key be depressed to add nine to the adding wheel of lowest order. On the forward stroke, as the shaft 17 turns in a counter-clockwise direction, the corresponding rack 24 rises, and thereafter, during the latter part of said stroke, the adding wheel frame 19 is rocked to move all of the gears 22 into mesh with their respective racks. 85 Also during the latter part of said stroke, the rollers 49 pass over the projections 180 and onto the high portions 182 of the cams 18. This causes the rockers 48 to be lifted 90 and, by engagement of the lips 60 thereon with the forward ends of the bail 56, to depress the rear end of the latter and then lift the same slightly. When the rear end of 95 said bail is depressed, engagement thereof 100 with the horn 281 of any previously operated carrying member 28 causes said member to be depressed and locked by its latch 25. Said bail is left in a position with its rear end slightly above the horns 281, as shown in Figure 3, and is locked in this position by engagement of its hook-shaped forward ends 560 with the offset portions of the latches 52, which latches are drawn into place beneath 105 said ends by their springs 53, as shown in Figures 3 and 4. During the return stroke or clockwise movement of the shaft 17, the rack 24 moves downwardly, turning the gear 22 and adding wheel 21 of lowest order, and as said adding wheel passes through the 110 "nine" and into the "zero" position, the corresponding carry control member or yoke 41 is disengaged from its latch 44 and operated by its spring 61 to cause the arm 412 thereof to disengage the latch 35 from the carrying 115 member 28 of the adding wheel of next higher order, as above explained. Said carrying member thereupon moves upwards slightly under the influence of its spring 34 until the horn 281 thereof engages the bail 56. Toward the end of the return stroke the adding wheel frame 19 is again rocked to move the gears 22 out of mesh with the 120 racks 24 and into engagement with the teeth 280 of the carrying members 28. Thereupon 125

engagement of the pins 55 on the cams 18 with the lips 54 of the latches 52 causes said latches to disengage the ends 560 of the bail 56, releasing the latter and permitting the 5 carrying member 28 corresponding to the adding wheel of higher order to move upwardly a distance limited by the length of the slots 32, which distance is sufficient to advance said number wheel of higher order 10 one space, as shown in Figure 5.

The re-setting of the parts takes place during the succeeding forward or counter-clockwise stroke of the shaft 17. As above explained, the projections 180 on the cams 18 15 cause the rockers 48 to be lifted, thereby depressing the rear end of the bail 56 and re-setting any carrying members which may have been operated, said carrying members being automatically locked in their normal 20 positions by their latches 35. When the rockers 48 are lifted, they also engage the extensions 50 of the bail 45, lifting said bail which, by engagement with the latches 44, restores the latter to the position shown in 25 Figure 2, the cam portions 440 of said latches rocking the carry control members or yokes 41 which are thereafter re-engaged by the locking shoulders 441 of said latches.

Having thus described my invention, I 30 claim:—

1. The combination with a plurality of registering elements, of means for carrying from an element of lower order to the element of next higher order, a member for controlling said carrying means, and means connected with said element of lower order for actuating said member, said member being adapted to permit said carrying means to operate only when it is moved by said actuating means and then released thereby.

2. The combination with a plurality of registering elements, of means for carrying from an element of lower order to the element of next higher order, a member for controlling said carrying means, means associated with said element of lower order for moving said member in one direction, and means for moving said member in another direction when released by said first named moving means to cause said carrying means to operate.

3. The combination with a plurality of registering elements, of means for carrying from an element of lower order to the element of next higher order, a member for controlling said carrying means, means for holding said member in a normal inoperative position, and means associated with said element of lower order for disengaging said member from said holding means and thereafter releasing the same, said member being adapted to permit said carrying means to operate only when released by said disengaging means.

4. The combination with a plurality of

registering elements, of means for carrying from an element of lower order to the element of next higher order, a member controlled by said element of lower order and adapted to permit said carrying means to operate only after it has been moved in one direction out of its normal position and then in the opposite direction into its operative position, and means for holding said member in a normal, intermediate, inoperative 75 position irrespective of the position of said element of lower order.

5. The combination with a plurality of registering elements, of means for carrying from an element of lower order to the element of next higher order, means for locking said carrying means against operation, and a member controlled by said element of lower order for unlocking said carrying means, said member acting to unlock said carrying means only when it is moved in one direction by said element and then released thereby.

6. The combination with a plurality of registering elements, of means for carrying from one element of lower order to the element of next higher order, means for locking said carrying means against operation, a member for unlocking said carrying means, means for moving said member in the direction to unlock said carrying means, means associated with said element of lower order for moving said member in the opposite direction, said carrying means being locked until said member has been moved 100 by said last named moving means to its full extent and then substantially returned by said first named moving means, and means for holding said member in an intermediate inoperative position irrespective of the position of said element of lower order.

7. The combination with a plurality of registering elements, of means for carrying from an element of lower order to the element of next higher order, means for locking said carrying means against operation, a member for unlocking said carrying means, means for holding said member in a normal inoperative position, means associated with said element of lower order for moving said member in one direction to disengage the same from said holding means, and means for moving said member in another direction when released by said first named moving means to unlock said carrying means.

8. The combination with a plurality of registering elements, of means for carrying from an element of lower order to the element of next higher order, means for locking said carrying means against operation, a member for unlocking said carrying means, a latch for restraining said member, and means associated with said element of lower order for unlatching said mem- 125 130

ber and permitting the same to unlock said carrying means.

9. The combination with a plurality of registering elements, of means for carrying from an element of lower order to the element of next higher order, means for locking said carrying means against operation, a member for unlocking said carrying means, a latch for restraining said member, means associated with said element of lower order for unlatching said member and permitting the same to unlock said carrying means, and mechanism for restoring said parts to their initial positions after the operation of said carrying means. 15

10. The combination with a plurality of registering elements, of means for carrying from an element of lower order to the element of next higher order, a member for controlling said carrying means, a cam carried by said element of lower order for moving said controlling member in one direction and thereafter releasing the same, and a spring for moving said member in another direction when released by said cam to cause the operation of said carrying means. 20

11. The combination with a plurality of registering elements, of means for carrying from an element of lower order to the element of next higher order, a member for controlling said carrying means, a latch for holding said member in a normal inoperative position, a cam carried by said element of lower order for moving said member in one direction to disengage the same from said latch, and a spring for moving said member in another direction when permitted by said cam to cause said carrying means to operate. 35

12. The combination with a plurality of registering elements, of means for carrying from an element of lower order to the element of next higher order, a member for controlling said carrying means, a latch for holding said member in a normal inoperative position, a cam carried by said element of lower order for moving said member in one direction to disengage the same from said latch, a spring for moving said member in another direction when permitted by said cam to cause said carrying means to operate, and means for re-engaging said latch with said controlling member, said latch having a cam portion for restoring said member to its normal position. 50

13. The combination with a plurality of registering elements, of slides co-operating with said elements respectively for carrying from an element of lower order to the element of next higher order, springs for operating said slides, latches for locking said slides against operation by said springs, and controlling members each actuated by an element of lower order for unlocking the 65

slide corresponding to the element of next higher order, each of said controlling members operating to unlock its carrying member only when it is moved in one direction by the corresponding element of lower order and then released thereby. 70

14. The combination with a plurality of registering elements, of carrying members associated with said elements respectively, springs for operating said carrying members, latches for locking said members, controlling members for releasing said latches, latches for holding said controlling members in normal inoperative positions, cams carried by said registering elements for moving the respective controlling members in one direction to release the same from their respective latches, and springs for moving said controlling members in another direction when released by their latches to cause the same to release said carrying member latches. 80

15. The combination with a plurality of registering elements, of carrying members associated with said elements respectively for carrying from an element of lower order to the element of next higher order, latches for locking the several carrying members against operation, a member controlled by said element of lower order for releasing said latches, said member acting to release said latches only when it is moved in one direction by said element of lower order and then released thereby, and a bail for re-engaging said carrying members with their respective latches. 90

16. The combination with a plurality of registering elements, of carrying members associated with said elements respectively for carrying from an element of lower order to the element of next higher order, latches for locking the several carrying members against operation, a member actuated by said element of lower order for releasing said latches, said member acting to release said latches only when it is moved in one direction by said element and then released thereby, a bail for re-engaging said carrying members with their respective latches, and a rocker for operating said bail. 100

17. The combination with a plurality of registering elements, of carrying members associated with said elements respectively for carrying from an element of lower order to the element of next higher order, latches for locking the several carrying members against operation, a member actuated by said element of lower order for releasing said latches, said member acting to release said latches only when it is moved in one direction by said element and then released thereby, a bail for re-engaging said carrying members with their respective latches, a rocker for operating said bail, and a latch for holding said bail in a position to permit 115

unlocking of said carrying members without permitting operation thereof by their springs.

18. In a register, in combination, a plurality of registering elements, actuators and carrying members for said elements respectively, a rocking frame in which said elements are mounted for moving the same into operative engagement with said actuators and carrying members alternatively, and a

member controlled by each of said elements and having a finger for controlling the carrying member of the element of next higher order, said members being pivotally mounted in said frame, and said fingers being normally concentric with the rocking axis of said frame. ¹⁵

In testimony whereof I affix my signature.

WILLIAM P. QUENTELL.
